United States Patent

Des. 241,931
Patented Oct. 19, 1976

241,931

SUSPENDED BUILDING

Richard W. Snibbe, 139 E. 18th St.,
New York, N.Y. 10003

Filed June 12, 1973, Ser. No. 369,383

Term of patent 7 years

Int. Cl. D25—03

U.S. CL. D25—30

FIG. 1.

FIG. 2.

FIG. 3.

FIG. 4.

FIG. 1 is a perspective upper rear and side view of the design of the invention showing means for suspending in dotted lines.

FIG. 2 is a perspective lower front and side view of the design of the invention showing means for suspending in dotted lines;

FIG. 3 is a front view in elevation of the design of the invention showing means for suspending in dotted lines; and

FIG. 4 is a side view in elevation of the design of the invention showing means for suspending in dotted lines.

The dotted line showing in the several views is for illustrative purposes only and forms no part of the claimed design.

I claim:

The ornamental design for a suspended building, as shown and described.
